(57) **CLAIM**

I claim the ornamental design for a trash can having dust pan cover with drop-down handle, as shown and described.

DESCRIPTION

FIG. 1 is a perspective view of a trash can having dust pan cover with drop-down handle embodying the design of the present invention, showing the handle in a raised position; FIG. 2 is a front elevational view thereof; FIG. 3 is a rear elevational view thereof; FIG. 4 is a right side elevational view thereof, the left side elevational view being a mirror image thereof; FIG. 5 is a top plan view thereof; FIG. 6 is a bottom plan view thereof; and, FIG. 7 is a perspective view of the trash can having dust pan cover with drop-down handle, similar to FIG. 1 but showing the handle in a lowered position.
